UNITED STATES PATENT OFFICE

ALFRED SOUTIER, OF QUINCY, MASSACHUSETTS

PROPELLER

Application filed August 2, 1932. Serial No. 627,277.

This invention relates to a propeller which is intended for general use and has for one of its important objects to provide, in a manner as hereinafter set forth, a propeller embodying a novel construction, combination and arrangement of parts through the medium of which the slip stream will be thrown rearwardly and outwardly around the fuselage of the aeroplane, thereby materially lowering head resistance.

Another important object of the invention is to provide a propeller of the aforementioned character including novel means for detachably mounting the blades on the propeller shaft.

Another important object of the invention is to provide an aeroplane propeller including a novel combination and arrangement of blades through the medium of which maximum efficiency will be had.

Other objects of the invention are to provide a propeller of the character described which will be simple in construction, strong, durable, reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation, showing a propeller constructed in accordance with the present invention.

Figure 2 is a view in front elevation thereof.

Figure 3 is a view in side elevation showing the propeller mounted on an aeroplane.

Figure 4 is a view in vertical transverse section, taken substantially on the line 4—4 of Figure 1.

Referring now to the drawings in detail, it will be seen that the reference numeral 1 designates a conventional aeroplane from the nose portion 2 of which a propeller shaft 3 projects. On the forward end portion of the shaft 3 is a circular head 4 having notches or recesses 5 in diametrically opposite sides

thereof. The head 4 constitutes what may be termed the hub of the propeller.

Mounted on the head 4 are forwardly diverging, outwardly curved blades 6. The inner ends of the blades 6 are provided with shanks 7 which are engaged in the notches or recesses 5 of the head 4. At their free ends the shanks 7 terminate in inturned lips 8 which are engaged with the rear face of the head 4. A retaining ring 9 is mounted on the head 4 for securing the shanks 7 in the notches or recesses 5. The retaining ring 9 is secured in position on the head 4 through the medium of a set screw 10.

On the rear sides and on the outer portions of the blades 6 are reversely curved fins 11. While the fins 11 are shown integral with the blades 6, it will be understood that said fins may be separate from the blades and secured thereon in any suitable manner.

Extending between the forward portions of the blades 6 and secured, at its ends, to said blades, as at 12, is a substantially spirally twisted strut which is designated generally by the reference numeral 13. The strut 13 constitutes a pair of integral propeller blades 14 which are connected by a reduced intermediate portion 15. As will be apparent, the strut 13 in addition to functioning as a propeller, constitutes means for bracing the blades 6.

It is believed that the many advantages of a propeller constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:

1. A propeller comprising a pair of blades, and means for mounting the blades on a propeller shaft, said means including a head fixed on the shaft and having notches in diametrically opposite sides thereof, shanks on the inner ends of the blades engaged in the notches, inturned lips on the free ends of the shanks engaged with the head, a ring encir-

clining the head and shanks for retaining said shanks in the notches, and means for securing the ring on the head.

2. A propeller comprising a hub, a pair of diverging, outwardly curved blades mounted on the hub, substantially reversely curved fins on the rear sides of the blades, and a substantially spirally twisted strut extending between the outer portions of the blades and connected thereto.

3. In combination with a shaft, a propeller mounted on said shaft, said propeller including a pair of diverging blades mounted on one end portion of the shaft and projecting beyond said one end of the shaft, and a spirally twisted strut extending between outer portions of the blades and connected at its ends thereto, said strut being spaced from said one end of the shaft.

20 In testimony whereof I affix my signature.

ALFRED SOUTIER.
